In Great Britain November 29, 1947

5 Claims. (Cl. 118—236)

1

This invention relates to machines for applying adhesive to paper and the like and has for its object to provide improvements in such machines.

With this object in view the invention provides a machine for applying adhesive to paper and the like comprising a support for a stack of sheets of paper or the like, a paper gripping device, means for adjusting the support towards and away from the gripping device, means for moving said gripping device to feed a sheet of paper to a roller coated with adhesive and means for peeling-off the paper from the roller and for guiding the paper onto a travelling belt or the like.

Means are provided for transmitting the desired motions to the various parts. The machine may be started automatically under control of another machine performing an operation other than applying adhesive to paper, or it may be started by hand. Means are also preferably provided functioning, when action is taken to stop the machine, to stop the machine automatically at the end of a cycle of operations. Means are also preferably provided for adjusting the distance of the table from the paper gripping device automatically according to the varying depth of the stack of papers. Means are also provided for applying adhesive to the roller and means for adjusting the thickness or depth of the adhesive coat applied to the roller. Still further means are provided for rendering the pneumatic gripping device operative and inoperative at the required times automatically.

The above and other features of the invention are set forth in the appended claims and are disclosed in the detailed description given by way of example, of the particular embodiment illustrated in the accompanying drawings in which:

Fig. 1 is a front elevation of a machine according to the invention;

Fig. 2 is a sectional side elevation of the machine, looking at the left of Fig. 1.

Fig. 3 is a detailed side view, on a larger scale, of the means for advancing the support for the stack of sheets of paper;

Fig. 4 is a part sectional elevation of a roller and clutch device therefor, for rotating the adhesive roller;

Fig. 5 is an end view of a suction member for lifting the topmost sheet of the stack; and

Fig. 6 is an underneath plan of the same.

Referring now to Figures 1 and 2 a suitable fixed framework 1 is provided for carrying the various parts and a horizontal main shaft 2

2

is provided at the lower end of this framework. The shaft 2 is normally idle but it has freely mounted on it a gear wheel 3 which is arranged to be continuously rotated through suitable gearing 4 from a convenient source of power such as motor 5. At predetermined intervals this gear 3 is locked to its shaft 2 by a clutch device consisting of a disc cam 6 fixed to the shaft a short distance away from the gear wheel and a clutch member 7 mounted on the shaft and slidable axially on a keyway between said cam 6 and gear 3 and biased by spring 8 into engagement with a complementary clutch member 9 associated with the gear 3. A bell crank lever device is also provided, one (upright) arm 10 of which is forked to engage the slidable clutch member 7 and is fixed to a spindle 11 and the other (horizontal) arm 12 of which is also fixed to spindle 11 and is arranged to be depressed by the cam 6 into a clutch release position to disengage the clutch. The cam does not engage the bell crank arm 12 directly but it engages a truck 13 which is fixed to a sleeve 14 and this sleeve 14 is axially slidable on a rod 15 having bearings in the horizontal arm 12 of the bell crank lever; the truck 13 is biased by spring 16 to a position whereat it underlies the cam 6. The outer end of the said sleeve has an enlarged head 17, and a tripping device such as a bell crank lever 18 is provided, one arm of which is forked to engage the said enlarged head 17, and said lever 18 may be actuated from a remote position by means of a rod 19, cable or other suitable connection.

In operation the clutch is normally disengaged by the highest part of the cam 6 engaging the truck 13 to hold the horizontal arm 12 of the bell crank lever down and the upright arm 10 in its farthest position away from the gear 3; hence the slidable clutch member 7 is held out of engagement with the gear clutch member 9. If now the trip lever 18 is tripped (e. g. under the control of another machine) the sleeve 14 carrying the truck 13 is moved axially by the trip lever 18 so as to move the truck 13 laterally out of the path of the cam 6, whereupon the bell crank is permitted to rock and the slidable clutch member 7 engages the gear clutch member 9 under the influence of the spring 8 biasing the slidable clutch member 7 towards the gear 3; the main shaft 2 now rotates. To stop the machine the trip lever 18 is returned to normal with the result that the truck 13 is again located in the path of the cam 6 and it will therefore be appreciated that when the shaft 2 has com-

pleted one revolution the highest part on the cam 6 engages the truck 13 to rock the bell crank against its spring 8; the effect of this movement is to disengage the clutch with the result that the shaft is automatically brought to rest at the end of a cycle of operations. The purpose of this arrangement is to provide for the machine being automatically started and stopped to carry out one or more complete cycles of operations for applying adhesive to one or more sheets of paper. A complete cycle of operations consists in energising a paper gripping device, picking up a sheet of paper from a supply, feeding the paper to a roller having a coating of gum, de-energising the paper gripping device and presenting a new sheet of paper from the supply to the gripping device.

The gripping device indicated at 20 (Figures 1, 2, 5 and 6) is located towards the upper end of the machine directly above the main shaft 2 and this device consists of a circular sectioned tube 21 parallel to the main shaft. This tube is closed at one end and is connected at the other end by a pipeline 80 to a suction pump (not shown) located at the lower end of the machine. The tube 21 is provided at intervals in its length with spaced branch tubes 22 open at one end to the longitudinal duct in the main tube and at the other end to divergent shallow grooves 23 in the lower face of a rectangular gripping plate member 24. A relief valve 25 (Figures 1 and 2) is also provided in the suction pipeline 80 of the pump, said valve being automatically opened and closed through the medium of a pivoted lever 26 and a cam 27 (hereinafter more fully referred to) on the main shaft.

The tube 21 is fixed at each end to a short upright bar or block 28 (Figure 2) slidable vertically in one end of an upright plate 29 which is itself slidable horizontally on fixed guides 30 (see also Figure 1). The tube 21 is therefore readily movable vertically and horizontally and for this purpose the upright bar or block 28 is connected to a vertical rod 31 engaging with a cam 32 on the main shaft 2 and the horizontally movable plate 29 is connected to the aforesaid pivoted lever 26 which is controlled by the aforesaid cam 27 on the shaft 2.

The under surface of the gripper plate 24 is normally located in close proximity, but at a comparatively small angle to the uppermost sheet of a stack 33 of sheets of paper to which adhesive is to be applied, with the result that because suction is applied (by the pump) to the grooves in the plate, that part of the uppermost sheet of paper opposite the plate is attracted to the plate and assumes an attitude inclined to the remainder of the sheet and urged against the underside of the plate; there is also a marginal part of the paper which projects beyond the raised edge of the plate. This stack 33 of paper is supported on a platform 34 which is mounted for vertical displacement (so as to feed the papers towards the gripping plate 24) by a stout rod 35 depending from it at the rear of the machine said rod being slidably mounted in an upright sleeve 36 located toward the lower end of the machine. This stout rod 35 has rack teeth 37 formed in it which are arranged to engage a pinion 38 fixed to a suitable cross shaft 39 and this shaft 39 and pinion 38 are rotatable by hand, by automatic means, or by both. For this purpose a ratchet wheel 40 (see also Figure 3) is also fixed to the shaft 39 and this wheel has a stop pawl 41 associated with it; there is also pro-

vided a hand wheel 42 (Figure 1) fixed to the end of the shaft 39 (having a lever control for the said stop pawl 41, if desired) in such manner that by turning the wheel (after first pressing the lever, if provided, to release the stop pawl), the shaft 39 may be rotated at will. For rotating the shaft 39 automatically a clawker 43 (Figure 3) is provided engaging the ratchet wheel 40 and this clawker 43 is controlled, through suitable links and levers 44 by a cam 45 on the main cam shaft 2.

It will be appreciated that the extent of upward movement of the platform 34 that would be required to feed the uppermost sheet of paper towards the gripping plate 24 after each operation would be much smaller than is normally provided for by ratchet mechanism and therefore there is also provided and adjustable bluffing plate 46 which is arranged to be interposed to varying extents between the clawker 43 and the ratchet teeth 40. For the purpose of controlling this plate 46 it is connected (through suitable links and levers 47, see also Figure 2) to a feeler device 48 which is biassed by a spring 49 downwardly into engagement with the upper surface of the stack of papers 33. It will be appreciated that the ratchet wheel 40 will be racked only when the bluffing plate 46 uncovers a new tooth on the ratchet wheel 40 and this stage is timed to take place at suitable intervals under control of the height of the stack of papers. The platform 34 is balanced by a weight 134 hanging from a cord or the like 234 which is coiled around the shaft 39. Immediately to the inner end of the platform 34 there is provided an upright wall 50 (Figure 2) which extends upwardly to a position slightly higher than the gripper plate 24 and its upper edge may be chamfered downwardly towards said gripper plate. Slightly spaced upwardly from this upper edge of the said wall 50 there is provided a roller 51 having a coating of adhesive. Adhesive is applied to this roller 51 by its engagement with another roller 52 preferably of larger diameter and this latter roller 52 dips into a trough 53 containing adhesive (which may be heated by electric heating element 153). These rollers 51, 52 are rotatable through suitable mechanism such as chains 53' and sprockets 54 by the main power source such as the motor 5; the lower roller 52 is adjustable (e. g. by screw means 54') towards and away from the smaller roller 51 to control the thickness of the adhesive coat applied to the latter and the trough 53 is preferably movable upwardly and downwardly into and out of its operative position by bars 55 depending from it and engaging with cams 56 fixed to a shaft 57 which is rotatable by a hand wheel 58; the cam 56 is so shaped as to hold the trough in its fully up and down positions.

Immediately above the small roller 51 there is provided a paper peeling device for peeling the paper off the roller 51 and this device consists of a plurality of spaced strip members 60 each having a tapered or curved part 61 which engage the surface of the roller in such manner as to peel the paper off the roller and guide it to a travelling band, belt or the like 62.

This belt 62 travels round end rollers 63 and is held in frictional engagement with a belt traversing roller 64 by an idler roller 65 which is biassed by adjustable spring plunger 66. The roller 64 is normally freely rotatable on constantly driven end stub spindle 67 (Figure 4) and a clutch device is provided by which the roller is clutched to the driven spindle once for each se-

quence of operations of the machine. The clutch device conveniently comprises a slideable clutch member 68 having a conical face 69 for engagement with a conical face 70 of the roller, a spring 71 biassing the said faces apart and a pair of clutch collars 72, 73 having inclined co-operating faces 74, 75. The collar 72 is free on the spindle 67 and is arranged for part rotation by movement of the aforesaid lever 26 through the intermediary of arms and links 76 (Figure 2). The collar 73 is fixed to the spindle 67, the result being that upon movement of the lever 26 the collar 72 is partly rotated, and because of the inclined faces 74, 75, imparts axial movement to the clutch member 68 against the spring 71 so that the roller is thereupon rotated. On the return motion of the lever 26 the roller is de-clutched by a reversal of the aforesaid clutching movements and the relief valve is permitted to close by its spring.

If desired there may be provided an idler disc 77 (Figure 2) bearing on the belt to ensure that the paper lays flat on the belt.

If desired also there may be provided a hole 78 in the upright wall 50 and a block 79 having a groove 80 connecting with said hole and with a lead from the blower side of the pump. The arrangement is such that at the appropriate time air is directed through the said hole to a location just below the uppermost sheet of paper in the stack so as to minimise the possibility of more than one sheet being raised by the gripping plate 24. It will be appreciated that the gripping plate 24 provides a good gripping surface for the paper and that by attracting the paper to it, so as to form a bend therein, the paper is readily picked up and carried to the adhesive coated roller 51 without the aid of guiding means such as a fixed rod. This is an important advantage because if a fixed guide rod is employed, and faults occur, paper is likely to foul the fixed rod and become entangled between the rod and the roller whereas by dispensing with said fixed rod the possibility of entanglement of the paper is considerably minimised.

The operation of the machine is as follows:

First the main shaft 2 commences to rotate by actuating the clutch mechanism, as before described, so as to rotate the cams 6, 27, 32 and 45. It should be first explained that the relief valve 25 is normally closed to maintain suction at the gripping device 24, which suction is applied to the uppermost sheet of paper, therefore the uppermost paper is, at this stage, gripped by the gripping member. The first cams to function (cam 27 and 32) operate the vertically slideable bar or block 28 and the horizontally slideable plate 29 to effect a combined raising and horizontal movement of the gripper plate 24 to move it toward the roller 51. Continued movement in this manner causes the leading edge of the paper to engage the adhesive coated roller 51, whereupon the paper adheres to the roller. At this stage the suction to the gripping bar is stopped by the lever 26 opening the relief valve, and subsequent movement of the paper is effected by the roller 51. The roller thereupon carries the paper upwardly, and partly over the top of the roller, and adhesive is picked up by the paper from the roller. In its travel partly over the roller the leading edge of the paper engages the inclined or curved edges of the peeling strips 60 whereupon these strips peel the said leading edge of the paper from the roller and curl it forward-

ly so as to guide the paper (with the assistance of disc 77) onto the travelling belt 62 in an inverted attitude with the adhesive uppermost. At a convenient stage the lever 26 operates the clutch of roller 64 to start the roller for traversing the belt.

During these operations the cam 45 associated with the platform raising ratchet wheel 49 functions to transmit one rack to the clawker 43 but as previously explained the action of the clawker on the ratchet wheel is controlled by the height of the stack of papers through the intermediary of the feeler device 48. The parts are returned to the original positions by subsequent movement of the respective cams and as also previously intimated the cycle of operations is completed by the time that the main shaft has completed one revolution. If in the meantime, the trip lever 18 has been re-set the shaft automatically stops rotating by the automatic disengagement of the clutch by cam 6. Alternatively the machine continues to operate on sheets of paper in succession until the trip lever is, in fact, re-set to permit automatic stopping of the machine at the end of a cycle of operations.

It will be appreciated that any or all of the cams and associated mechanism particularly those cams and levers which move the gripping plate may if desired be duplicated at each side of the machine.

We claim:

1. A machine for applying adhesive to paper sheets in succession, on one side thereof, comprising a frame, a driving shaft therein, a rising and falling support in the frame for a stack of sheets, a first cam means on the driving shaft for raising the support as the stack of sheets is consumed, a coating roller in the frame and means for driving it, a tank for adhesive and a furnishing roller for supplying adhesive from the tank to the coating roller, a sheet lifting suction device, vertical guides supporting the suction device above said support, a second cam means on said driving shaft for raising and lowering said suction device in its guides, and a further cam means on the driving shaft for moving said guides towards and away from the coating roller, a suction conduit leading to the said suction device, a relief valve included in said suction conduit, and means operated by said further cam means for opening said relief valve when the suction device is nearest the coating roller.

2. A machine according to claim 1, having a clutch means in the drive to said driving shaft, and interrupting means on the driving shaft for interrupting the operation of the driving shaft only upon the completion of a cycle of operations on a sheet.

3. A machine according to claim 1, having peeler for stripping the sheet from the coating roller and for disposing it adhesive side uppermost, and a travelling band to receive and carry away the sheet when stripped.

4. A machine according to claim 1, wherein the suction device includes an elongated hollow gripping plate having a number of suction tubes leading thereto on its upper side, and having a corresponding number of outlets in its underside each of which has radiating grooves in the surface of the plate giving a suction effect substantially along the whole length of the plate.

5. A machine according to claim 1, wherein the driving means for the coating roller includes a constantly-driven shaft, a normally-open clutch between said shaft and roller, and means

operated by said further cam means for engaging the clutch when the said guides approach the coating roller.
